C. H. PETERSSON

LATCH

Filed June 13, 1924

UNITED STATES PATENT OFFICE.

CARL HJALMAR PETERSSON, OF GOTTFENBORG, SWEDEN.

LATCH.

Application filed June 13, 1924. Serial No. 719,903.

To all whom it may concern:

Be it known that I, CARL HJALMAR PETERSSON, a subject of the King of Sweden, residing at Gottenborg, Sweden, have invented certain new and useful Improvements in Latches; and I do hereby declare that the following is a full, clear, concise, and exact description of the invention, such as will enable others skilled in the art to 10 which it appertains to make and use the same.

The present invention relates to latches for windows, doors and the like having a pivotable bolt connected with a movable bolt-actuating member by means of which the bolt can be moved into latched or unlatched position.

The invention has for its main object to provide simple and reliable means for transmitting the movement between said bolt-actuating member and bolt.

One embodiment of the invention is illustrated in the accompanying drawing wherein Figures 1 and 2 show side elevations of the latch in unlatched and latched position. Figures 3 and 4 are sections of the latch on the lines I—I and II—II in Figures 1 and 2 respectively and with the parts in corresponding operative positions.

The latch shown in the drawing is provided with three latching bolts, an upper bolt 14, an intermediate bolt 1 and a lower bolt 15. A latch-casing 16 is provided for each of the bolts 14 and 15 which may be of any known construction and, therefore, these bolts are not shown in details. By means of a member 4 rotatably journalled in a casing 161 and provided with a hole 17 for the spindle of a handle (not shown) and rods 13 connected with the member 4 by means of links 181 all of the bolts are operated.

The bolt 1 is pivotably journalled on a pin or pivot 5 carried by lugs 51 on the rear side of the latch-plate 11. The bolt 1 when moved into latching position, as shown in Figures 2 and 4, projects through a recess or an opening 12 in said plate. The bolt 1 receives its motion from one of the rods 13 by means of a link or links 3 which by a pin or pivot 10 is or are hinged to said rod and by a pin or pivot 9 to an intermediate member 2. This member is provided in a recess 18 in the bolt 1 and hinged to the latter by a pin or pivot 7 which is substantially parallel with the pin or pivot

5 of the bolt. The pivots 9, 10 are, practically, mutually parallel and are disposed about perpendicularly to the pivots 5, 7.

It might be understood that I do not desire to limit my invention to the embodiment above described with reference to the drawing. The bolt 1 may, for inst., be connected with a rotatable member, for inst. such a one similar to the member 4, directly by means of the link or links 3. The number of the bolts may, naturally, also be varied according to the circumstances in which the latch is to be used.

What I claim is:—

1. A latch comprising in combination a base plate, a bolt pivotally connected to said base plate and adapted to swing into latching position through an opening in said base plate, a bolt actuating member moving in a plane substantially perpendicular to the plane of movement of said bolt, an intermediate member pivotally connected to said bolt, a link having its opposite ends connected to said intermediate member and bolt actuating member, the pivot connecting the bolt with the intermediate member being substantially parallel with the pivot connection between said bolt and base plate, and the pivots connecting the link with said intermediate member and bolt actuating member respectively, lying in a plane at substantial right angles to the first connection of said bolt and base plate.

2. A latch comprising in combination a base plate, a bolt pivotally connected to said base plate and adapted to swing into latching position through an opening in said base plate, a sliding rod movable substantially parallel with the pivoting axis of said bolt for operating the same, an intermediate member pivotally connected to said bolt, a link pivotally connected at one end to said rod, the opposite end of said link being pivotally connected to said bolt, the pivot connections of said bolt extending parallel to one another, and the pivot connections of said link extending parallel to one another and at right angles to said bolt pivot connections.

3. A device of the character described comprising a base plate, a swinging bolt pivotally connected to said base plate, sliding bolts, bolt actuating means for jointly connecting said bolts, a sliding rod included in said bolt actuating means, an intermediate member pivotally connected to said

swinging bolt, a pair of parallel links each having one end connection to said intermediate member, and the opposite ends of said links being pivotally connected to said rod whereby upon the sliding of said rod, said swinging bolt will be moved to locked position.

4. A latch of the character described comprising a base plate, a swinging bolt pivotally supported thereupon and having a recess therein, an intermediate member having one end seated within said recess, a pin

extending through said bolt and intermediate member forming a pivotal connection therebetween, a bolt actuating means, a link included in said bolt actuating means and a pin extending through said intermediate member and link forming a pivot connection therebetween extending at right angles to the pivot connection between the bolt and intermediate member.

In witness whereof I have hereunto set my hand.

CARL HJALMAR PETERSSON.
